UNITED STATES PATENT OFFICE.

JAMES M. SEYMOUR, OF NEWARK, NEW JERSEY.

METHOD AND MEANS FOR VENTILATING VEHICULAR TUNNELS.

1,418,980.

Specification of Letters Patent. Patented June 6, 1922.

Application filed January 20, 1921. Serial No. 438,593.

To all whom it may concern:

Be it known that I, JAMES M. SEYMOUR, a citizen of the United States, residing at Newark, in the county of Essex and State of New Jersey, have invented certain new and useful Improvements in Methods and Means for Ventilating Vehicular Tunnels; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to a novel method and means for ventilating subterranean and submarine tunnels; and the invention has reference, more particularly, to a novel method and arrangement of structure for ventilating vehicular tunnels in which motor vehicles are permitted to travel.

The present invention has for its principal objects, first, to provide a novel method of ventilating vehicular tunnels, whereby a large volume of air at comparatively low pressure can be moved through the tunnel drift at a comparatively low cost, instead of employing a small volume of air delivered at high pressure requiring expensive construction of special ducts and ventilating passages, and necessitating a high expense both as to installation and upkeep. Furthermore, the present invention provides a method of ventilating whereby a large volume or current of air is delivered to and moved through the tunnel at higher speed than and in the direction of travel of motor vehicles there-through, so as to not only maintain a healthy and safe atmospheric condition within the tunnel at all times, but also resulting in a considerable reduction of power costs in operation.

Secondly, it is the object of the present invention, from the construction standpoint, to provide a very simple and comparatively cheap tunnel construction, eliminating the necessity of especially arranged air channels or ducts, so that comparatively the entire capacity of the tunnel, not occupied by the vehicles moving therethrough may be utilized as the air conduit. Such construction eliminating cross currents and eddies in the air stream, and loss of velocity of the air

current through compelling the same to traverse the highway of the tunnel laterally from an air delivery duct to an air discharge duct. And, furthermore, the invention entails a comparatively simple structural combination of air moving and controlling elements, which are comparatively cheap as to installation, and which, in operation reduce to a minimum the fixed charge for power required to operate the same, thus affording ventilating means requiring but low cost for upkeep.

Other objects of the present invention, not at this time more particularly enumerated, will be clearly understood from the following detailed description of the same.

With the various objects of the invention in view the same consists, primarily, in the novel method of ventilating a vehicular tunnel, as well as in the novel structural combinations by means of which said method may best be employed.

The invention is clearly illustrated in the accompanying drawings, in which:

Figure 1 is a longitudinal vertical section of a vehicular tunnel provided with air delivery and control means embodying the principles of the present invention, and adapted to carry out the novel method of ventilation involved in the present invention; and Figure 2 is a detail horizontal section through an entrance portion of said tunnel so equipped and constructed.

Similar characters of reference are employed in the above described views, to indicate corresponding parts.

Referring now to said drawings, the reference character 1 indicates a suitably constructed tunnel providing a continuous interior passage or way 2 from its entrance to its discharge end. The reference character 3 indicates the way leading to the entrance portal or entrance end 4 of said tunnel.

Constructed and located intermediate said way 3 and said entrance portal or end 4 of the tunnel 1 are one or more locks. In the illustration of my invention shown in the accompanying drawings I have chosen to provide three such locks in parallel or side by side relation, to wit, the locks, 5, 6 and 7. Each lock is provided with a pair of suitably constructed and operated lock doors or gates 8 at their receiving or entrance ends, and with a pair of similar lock doors or gates 9 at their discharge or exit ends. It is

desirable, in practice, that each lock be long enough to accommodate at one time from six to eight motor vehicles, although, of course, it will be clearly understood that the same 5 may be modified in such particular to suit the requirements of the particular tunnel location.

Suitably located and housed above the tunnel entrance and its locks are a plurality of 10 fresh air impelling mechanisms of any desired type, such, for example, as the rotary fans 10 shown in the drawings. These air impelling mechanisms are connected through suitably disposed air delivery conduits or 15 passages 11 with the entrance portal or end 4 of the tunnel at a point somewhat beyond the inner or discharge ends of the locks 5, 6 and 7. Suitable shut-off valves or gates 12 with the required operating mechanism may 20 be provided in connection with each air delivery conduit or passage, whereby the volume of air delivered may be either variously controlled or entirely cut off if desired.

The method of ventilating a vehicular 25 tunnel, particularly designed to accommodate motor vehicular traffic, and which may put in effect by the above described structure, consists in delivering into the entrance end of the tunnel and impelling there- 30 through to the exit end thereof, or other suitable venting points, a large volume of air at comparatively low pressure, said air being caused to travel through the tunnel passage or way with or in the direction of 35 traffic movement, and at velocity in excess of or greater than the permitted speed of vehicles moving therethrough, thus utilizing practically the entire area of the tunnel as a fresh air conduit. To assure proper and 40 continuous directional flow of the air stream thus permitted, checks against backward escape of air from or through the vehicular entrances to the tunnel are provided, of such a nature that comparatively rapid ac- 45 cess to the tunnel interior by vehicles may be attained without in any way interrupting or disturbing the directional flow of the air, or diminishing the desired volume of the air stream. By virtue of such method, a 50 comparatively large volume of air at low pressure may be moved at desired velocity through the tunnel interior, with a relatively small expense for power. Since the air is impelled through the tunnel in the 55 direction of traffic and in company with the vehicles moving through the tunnel, said vehicles will not impede the flow of air, but will really aid in maintaining said flow, and will tend to prevent lagging of the air 60 stream.

In cases where a single lock is employed the inner lock gates 9 at the discharge end of the lock are closed against backward and outward flow of air tending to check and 65 interfere with the continuous flow of air

through the tunnel, and the outer lock gates 8 are opened, so that vehicles may be driven into the lock. When the lock is filled with vehicles, or it is otherwise deemed advisable to permit the passage of vehicles from the 70 lock into the tunnel, the outer lock gates 8 are closed, and the inner lock gates 9 are opened, so that the lock is thrown into communication with the tunnel way 2, and the vehicles are free to enter. The lock being 75 opened to communication with the tunnel, the outer lock doors 8 serve to prevent backward escape of the ventilating air under such conditions.

In cases where two or more locks are employed, as shown in the drawings, the locks are manipulated successively to open and close the same to the entrance and exit of vehicles, so that while the group of cars 80 locked in one or more locks are being liberated for entrance into the tunnel, the remaining lock or locks are closed to communication with the tunnel, while opened to the entrance of vehicles thereinto from the tunnel approach or way 3.

I am aware that in detail my invention, from the structural standpoint may be variously modified, both as to construction and arrangement of the parts and devices employed, without departing from the general scope and principles of the said invention, hence, I do not limit myself to the exact arrangement and relations or construction of parts as above described, or as illustrated in the accompanying drawings.

I claim:—

1. A method of ventilating vehicular tunnels, comprising the impulsion of a large volume of air through the tunnel way from the entrance to the exit thereof, and locking 105 said air against backward escape from the tunnel entrance while vehicles are being admitted for entrance into said tunnel.

2. A method of ventilating vehicular tunnels, comprising the delivery of a large 110 volume of air into the tunnel entrance, impelling said air through the tunnel way in the direction of traffic movement for discharge at or near the exit end of the tunnel, and locking said air against backward escape from the tunnel entrance while vehicles 115 are being admitted for entrance into said tunnel.

3. A method of ventilating vehicular tunnels, comprising the delivery of a large 120 volume of air at low pressure into the tunnel entrance, impelling said air through the tunnel way in the direction of traffic movement and at a velocity in excess of the permitted speed of traffic movement, discharging said air at or near the tunnel exit, and locking said air against backward escape from the tunnel entrance while vehicles are being admitted for entrance into said tunnel.

4. The combination with a vehicular tun- 125

nel of means for delivering to and continuously moving air through said tunnel from its entrance to its exit end, and an air lock at the tunnel entrance providing means for admitting vehicles to said tunnel while preventing backward and outward escape of air from said tunnel entrance.

5. The combination with a vehicular tunnel of air moving machinery, a conduit for delivering air from said air moving machinery into the entrance of said tunnel for continuous movement through the tunnel way from its entrance to its exit end, and an air lock rearward of the discharge end of 10 said delivery conduit and adapted to communicate with said tunnel entrance providing means for admitting vehicles to said tunnel while preventing backward and out-

ward escape of air from said tunnel entrance.

6. The combination with a vehicular tunnel of air moving machinery, a conduit for delivering air from said air moving machinery into the entrance of said tunnel for continuous movement therethrough toward 25 the exit end of the same, and an air lock at said tunnel entrance having inner and outer lock doors.

In testimony that I claim the invention set forth above I have hereunto set my hand 30 this 15th day of January, 1921.

JAMES M. SEYMOUR.
